UNITED STATES PATENT OFFICE.

NORMAN LIPSKY, OF NEW YORK, N. Y., ASSIGNOR TO HENRY HYMAN & COMPANY, INC., A CORPORATION OF NEW YORK.

DESIGN FOR A LIGHTING-FIXTURE BRACKET.

Application filed May 15, 1923. Serial No. 6,166. Term of patent 3½ years.

To all whom it may concern:

Be it known that I, NORMAN LIPSKY, a citizen of Russia (having taken out first papers), residing in the borough of Manhattan, city, county, and State of New York, have invented a new, original, and ornamental Design for a Lighting-Fixture Bracket, of which the following is a specification, reference being had to the accompanying drawing, forming part thereof.

The figure is a face view of a lighting fixture bracket showing my new design.

I claim:—

The ornamental design for a lighting fixture bracket as shown.

In testimony whereof, I have affixed my signature to this specification.

NORMAN LIPSKY.
